FRANK E. PELLS AND JESS CHRISTENSEN, OF SEATTLE, WASHINGTON.

STAMP-CANCELING DEVICE.

1,127,806.

Specification of Letters Patent.

Patented Feb. 9, 1915.

Application filed November 22, 1913. Serial No. 802,449.

To all whom it may concern:

Be it known that we, FRANK E. PELLS and JESS CHRISTENSEN, citizens of the United States, residing at Seattle, in the county of King and State of Washington, have invented a certain new and useful Improvement in Stamp-Canceling Devices, of which the following is a specification.

Our invention relates to improvements in stamp canceling devices and more particularly to improvements in such devices that are adapted for canceling postage stamps that are affixed to packages to be transported by the parcel post branch of government mail service, and the object of my improvement is to provide a simple and inexpensive self-inking postage stamp canceling device that may be rolled over the postage stamps of a package or parcel to cancel such stamps without striking such package a violent blow as has been necessary heretofore when using the ordinary flat faced hand-stamp. We accomplish this object by the device illustrated in the accompanying drawings, wherein—

Figure 1 by a plan view represents a stamp canceling device embodying our invention; Fig. 2 illustrates the same by a view in side elevation, certain parts being broken away more clearly to show other parts, Fig. 3 is a view in horizontal cross-section on broken line y, y of Fig. 2, and Fig. 4 illustrates a detail of my invention.

Referring to the drawings, in which like reference numerals indicate like parts, 5 and 6 constitute portions of a two part handle, and 7 and 8 are side plates that are attached respectively to like ends of the handle parts 5 and 6 to adapt them, when the two parts 5 and 6 of the handle are secured together, to form a U shaped bracket on the end of the handle.

9 is a type wheel that is pivotally mounted on a pivot 10 to rotate thereon between the side plates 7 and 8 through which the pivot shaft 10 extends as at 10', such pivot shaft 10 being provided with a shoulder on one of its ends and with a screw-thread on its other end, such shoulder engaging with the side plate 7 while the screw-threaded end screws into and through the side plate 8 to project outwardly therefrom, a nut 11 being screwed on such projecting end portion to engage against the outer surface of the side plate 8 to prevent the pivot shaft 10 from turning.

An ink-wheel or rotatable pad 12 which

may be made of any suitable absorbent material, as felt, normally bears against the type wheel 9 to ink the face of the type thereon. The said ink-pad 12 is disposed to rotate upon a pivot shaft 13 which is disposed to extend through longitudinal slots 14, 14 provided in each of the side plates 7 and 8 whereby such pivot shaft 13 with the ink-wheel 12 mounted upon it may be moved sidewise always to engage with the face of the type on the type wheel 9 irrespective of changes in the diameter of the ink pad 12 due to wear. The ink pad 12 is larger in diameter than the type wheel 9 so that it may be readily supplied with ink by rolling it over the surface of a plate or flat ink pad without interfering with the type 9 such plate or flat ink pad being smeared with a supply of ink.

A member 15, of U shape, is provided with notched ends 16, 16, as shown in Fig. 2, and with a shank 17, as shown in Fig. 3, and is disposed to adapt it to engage with the pivot shaft 13 adjacent to either side of the ink pad 12, the said shank 17 being disposed to project within a recess that is provided in an adjusting bar 19 that extends lengthwise within a recess 18 that is formed in the handle parts 5 and 6. A helical compression spring 20 is provided on the shaft 17 and adapted to exert pressure against the member 15 to cause such member 15 to bear against the end portions of the pivot shaft 13 to keep the ink pad 12 in contact with the type 9, one end of such spring 20 bearing against the end of the adjusting bar 19 which is threaded on its outer end and adapted to screw within a sleeve 21 which sleeve 21 is provided with a collar 22 that fits within suitably formed recesses provided in the handle parts 5 and 6 thus to prevent such sleeve 21 from endwise movement but adapting it for rotary movement. The two parts 5 and 6 of the handle are secured together by screws 24, 24, as shown in Fig. 2, while the plates 7 and 8 are secured in their relative positions at their outer ends by the pivot shaft 10. The tension of the spring 20 may be increased or diminished by turning the sleeve 21 to move the bar 19 lengthwise within the handle parts 5 and 6.

Any desired combination of letters, words or characters, may be supplied upon the periphery of the type wheel 9, as, for instance, the name of a post office, date of mailing and a numeral or letter indicating the name

of the operator may be stereotyped to form a copper strip and such strip may be then bent around and attached to the periphery of such type wheel 9 and there secured by pins or solder; or separable type may be disposed to project radially from radial holes formed in such type wheel 9; or some of the characters may be removable while other characters may be permanently attached to the periphery of such type wheel 9.

In Fig. 4, by a view upon an enlarged scale, we have shown in cross-section one plan of securing a movable type 25 in a radial hole in a type wheel 26 by means of a screw 27 so that the faces of such movable type 25 may register with the faces of the fixed type 28.

Obviously minor changes in the construction and arrangements of the parts of a structure embodying our invention may be made without departing from the spirit thereof.

Copies of this patent may be obtained for five cents each, by addressing the "Commissioner of Patents, Washington, D. C."

What we claim is:

In a device of the class described, the combination of a hollow handle, bracket arms carried by one end of said handle, a type roller rotatably-mounted in the outer ends of said arms, an inking roller yieldingly-mounted in said arms, a forked member engaging the inking roller and extending into the hollow handle, a spring surrounding said forked member, and means disposed within the handle and operable from the outer end thereof for controlling the tension of the spring.

In witness whereof, we hereunto subscribe our names this sixth day of November A. D., 1913.

FRANK E. PELLS.
JESS CHRISTENSEN.
